17 Claims. (Cl. 179—18)

This invention relates to telephone systems and particularly to systems comprising automatic switching equipment for completing desired connections.

5 It is the object of the invention to increase the flexibility and efficiency of automatic switching equipment in telephone systems.

In telephone systems comprising automatic switches for establishing desired connections, it is 10 known to provide digit registering and translating means for controlling the operation of switches through which a desired connection may be established.

A feature of the invention is the provision of 15 means in a telephone system comprising automatic selector switches for translating the position to which a selector switch, through which the establishment of a desired connection is attempted, into the code of an alternative route for 20 use in controlling the reoperation of this switch and the operation of such other switches as may be included in the alternative route.

Another feature of the invention is the connection of a register switch to a selector which 25 has encountered an all-trunks busy condition and the advance of the register switch to a position dependent upon the identity of the trunk group in which all trunks were found busy. If the selector is a two-digit switch the register switch is 30 first advanced to a level corresponding to the level of the selector in which the selected trunk group is located; and then the register switch and the selector switch are advanced step by step in synchronization in these levels until the selector 35 switch reaches its ultimate off-normal position, whereby the position of the register switch indicates the identity of the busy trunk group.

The invention and its features will be better understood by considering in detail a multi- 40 office telephone system in which the invention is embodied, one such embodiment being represented schematically in Figs. 1, 2 and 3 of the drawings which form a part of this specification and another embodiment being represented 45 schematically in Figs. 4 and 5 of the drawings. The invention may be applied to the selector and switch controlling devices of other systems by any one skilled in the art. Referring to the drawings:

50 Fig. 1 shows a two-digit two-motion selector OS;

Fig. 2 shows the register switch VR of a special translator and a finder switch F for connecting the translator to any one of a group of selectors;

55 Fig. 3 shows a portion of a translating switch

TS operatively associated with the register switch of Fig. 2;

Fig. 4 shows a single digit two-motion selector switch OS4 and a link comprising finder switches SF and RF; and

Fig. 5 shows a register-controller RC connected through the switches SF and RF of Fig. 4 to the selector switch of Fig. 4.

In the drawings the contacts of the various relays and magnets are designated by lower case letters, corresponding to the capital letters by which the windings of these elements are identified; the digit following the lower case letter designation distinguishes each contact spring of a relay or magnet from the other contact springs of the same element.

The outgoing group selector of Fig. 1 comprises a vertical magnet VM, rotary magnet RM, release magnet ZM, a vertical commutator VW, a terminal bank and two sets of brushes; one set consisting of brushes —1, +1, and P1 and the other set consisting of brushes —2, +2, and P2. This selector is adapted to be selected and seized, if idle, by a first selector which is set in accordance with the first of three office code digits transmitted by a register-translator, neither the first selector nor the register-translator being shown in the drawings. After seizure the selector of Fig. 1 is operated under the control of the second digit transmitted by said register-translator to select a level of the terminal bank and by the third digit transmitted by the register-translator to select the desired group of terminals in the selected level. The selector of Fig. 1 thereupon hunts for an idle set of terminals in the selected group and extends the connection over the junction connected to this set of terminals to the called office or exchange. If no junction is available, the brushes are stopped on the last set of terminals in the selected group and in certain cases, it is possible to route the call over a different group of junctions to another office and through this other office to the desired exchange. The completion of a call over an alternative tandem route is desirable, of course, only when 45 all of the direct junctions to the called exchange are busy.

The reoperation of a selector switch OS to select an alternative group of junctions is controlled by the special translator shown in Figs. 2 and 3. The finder switch F comprises a magnet FM, a set of brushes fm1, fm2, fm3, fm4, fm5 and fm6, and a bank of terminals to which are connected one or more groups of outgoing group selectors OS. The special translator comprises a

register switch VR and a translator switch TS. The register switch has a vertical magnet VM2, a rotary magnet RM2, a vertical commutator, a terminal bank and brushes *vrml* and *vrm2*. The 5 segments of the vertical commutator of the register switch are connected to the corresponding segments of the vertical commutators of all the selectors OS to which the translator is common.

The translator switch TS shown in Fig. 3 is of 10 the kind described in Patent 1,900,969, granted to E. P. G. Wright, March 14, 1933 and in Patent 1,903,019, granted to E. P. G. Wright et al., March 28, 1933. Each level of the translator switch is connected to a position of the register switch of 15 Fig. 2, which position represents the translated characteristics of a group of direct junctions for which there is an alternative route.

The operation of selector OS and the operation of the special translator, in consequence of 20 of the selector OS finding all junctions in a desired group busy, will be described in detail. When a subscriber makes an outgoing call, the digits dialed are received by a register-translator which transmits three code digits, the first of 25 which sets a first code selector, and the second and third of which set a two-digit outgoing selector OS of Fig. 1. When the outgoing group selector OS is seized by a first selector (not shown), relay A is operated in a circuit from 30 battery through its right winding, back contacts of springs *hs5*, *hb2*, *ha2* and *el3* over the — conductor incoming from the first selector, through the controlling register-translator (not shown), back over the + conductor, back contacts of 35 springs *el5*, *ha3*, *hb3*, *hs6*, and left winding of relay A to ground. Relay A closes a circuit at the front contact of spring *a1* for operating relay B; and relay B closes a circuit for operating relay C from the winding of relay C, vertical off- 40 normal contact *n2*, rotary off-normal contact *nr2*, contacts *b3*, *ha5* and *hb5* to ground. Relay A is alternately released and reoperated in response to the impulses of the second code digit when transmitted by the register-translator. 45 Each release of relay A closes at the back contact of spring *a1* a circuit for energizing the left winding of relay C and the winding of vertical magnet VM, thereby raising the brushes of the switch up to the level corresponding to the digit 50 transmitted. Being slow in releasing, relay B remains operated during the response of relay A to each digit received. The circuit for operating relay C is opened at contact *n2* when the switch moves out of normal position but relay C is held 55 by its left winding until all of the impulses of the second code digit have been received by relay A. The release of relay C closes a circuit through the winding of relay E, contact *n1*, back contact of spring *c4*, rotary off-normal contact 60 *nr2*, contacts *b3*, *ha5* and *hb5* to ground. Relay E operates, transferring at spring *e5* the left winding of relay C from magnet VM to magnet RM and closing at contact *e3* a circuit for re-operating relay C. At spring *c4*, relay C opens 65 the operating circuit and closes a locking circuit for relay E. Relay A then responds to the impulses of the third code digit when transmitted from the register-translator, each release of relay A closing the circuit for operating magnet RM, 70 the brushes being thereby advanced by magnet RM into engagement with the first set of terminals in the desired group of the selected level. When the brushes are advanced out of the normal rotary position opposite the selected level, 75 the rotary off-normal springs are actuated, con-

tact *nr2* being effective to hold open the operating circuit for relay E. When all of the impulses for the third code digit have been received, relays C and E are released in succession. While relay E is releasing, the first two sets of terminals in the selected group are tested. If the set engaged by the upper set of brushes is idle, relay HA is operated by the current in a circuit from ground through contact *b1*, vertical off-normal contact *n3*, back contact of spring *hb1*, 10 winding of relay HA, rotary off-normal contact *nr1*, contact *c1*, front contact of spring *e4*, contact *hs1* and through the right winding of relay G to battery. Relay G is marginal and does not operate at this time. Relay HA closes a locking 15 circuit through its contact *ha1*; and, at its front contact *ha4*, connects ground from contact *b1* to the test brush *P1* to guard the selected junction from seizure by any other hunting selector. The operation of relay HA extends the connection 20 from the first selector through the front contacts of springs *ha2* and *ha3*, and through brushes —1 and —2 to the junction connected to the terminals with which these brushes are in engagement. The opening of contact *ha5* prevents the 25 reoperation of magnet RM after relay E releases.

If the set of terminals engaged by the upper set of brushes is busy, but the set of terminals engaged by the lower set of brushes is idle, the busy ground potential encountered on the test terminal with which brush *P1* is in engagement is effective by its connection through the back contact of spring *ha4* and contact *b4* to short-circuit the winding of relay HA so that relay HA does not operate and relay G operates. Relay G 35 closes a locking circuit from battery through contact *g4*, left winding of relay G, contact *g2*, front contact of spring *b5*, vertical off-normal contact *n5*, and contacts *ha5* and *hb5* to ground. With relay HA normal and relay G operated, a circuit 40 is closed for operating relay HB; this circuit is traced from battery through the winding of relay HB, back contact of the eleventh step spring *s1*, contacts *g5*, *n3* and *b1* to ground. Relay HB locks through the front contact of its spring *hb1*; 45 and the opening of the back contact of this spring prevents the operation of relay HA when relay E releases. Relay G releases when relay HB operates. With relay HA normal and relay HB operated, the connection from the first selector 50 is extended through the back contacts of springs *ha2* and *ha3* and the front contacts of springs *hb2* and *hb3*, and through the brushes —2 and +2 to the junction connected to the terminals with which these brushes are engaged. The operation of either of relays HA or HB causes the 55 release of relay A and the release of relay A causes the release of relay B, the ground potential for holding whichever one of relays HA or HB is operated being supplied from the seized 60 junction through the brush *P1* or *P2* as the case may be. The register-translator controls the operation of the remaining switches required for completing the desired connection. When the connection is released, the disconnection of the 65 holding ground potential from the test conductor P causes the release of relay HA or HB and operation of release magnet ZM in a circuit through the back contact of spring *b5*, vertical off-normal contact *n5*, and back contacts *ha5* and *hb5*. 70 When the switch reaches normal the circuit for operating magnet ZM is opened at contact *n5*.

If both sets of contacts, with which the upper and lower sets of brushes are in engagement, are busy when relay C releases at the end of the 75

group selecting operation of magnet RM, the ground potential encountered by brush P2 is connected through the back contact of spring hb4 and contact g4 to short-circuit the winding and thereby prevent the operation of relay HB. The operating circuit through the right winding of relay G having been opened by the release of relay E and the left winding of relay G being short-circuited by the busy ground potential encountered by brush P2, relay G releases closing a circuit for operating the rotary magnet RM; this circuit is traced through contact e1, the back contact of spring hs1, contact g1, rotary off-normal contact nr2, and contacts b3, ha5 and hb5 to ground. The operation of magnet RM steps the brushes to the next sets of terminals in the group which are tested in the manner hereinbefore described, except that the test circuit through the right winding of relay G is closed through the contact rm1 while magnet RM is releasing instead of through the front contact of spring e4. The selector is provided with an additional brush D and associated terminals for use in determining whenever the brushes are advanced to the last terminal of a group without finding any line in the group idle. To this end the contact g3 of relay G is connected to each of the terminals in the selected level with which brush D engages when advanced to the last position of a group; so that, if all of the junctions in a selected group are busy, a circuit is closed from the busy ground potential encountered by brush P2, through the back contact of spring hb4, contact g3, terminal and brush D, contact c2, and lower winding of relay HS. Relay HS operates and closes at its contact hs4 a locking circuit through its upper winding, the front contact of spring b5, contacts n5, ha5 and hb5 to ground. Relay G releases but the circuit through contact g1 for reoperating magnet RM is held open at the back contact of spring hs1. At contacts hs5 and hs6 the connection of the incoming conductors — and + to the windings of relay A is interchanged so as to reverse the current over these conductors and through the register-translator which in known manner thereupon stops the transmission of digit impulses until the normal direction of current is restored.

All of the junctions in the selected group having been found busy and relay HS operated, a start circuit is closed for initiating the operation of the finders of all idle special translators in order that one of these translators be associated with the selector OS in question. This start circuit is traced from battery through contact hs3 and over conductors S, through the off-normal contact n1 and contact b6 of relay B2 of each idle translator, to the upper winding of the start relay ST of each such translator. Relay ST closes a circuit from battery through the winding of finder magnet FM, contact st2, back contact of spring p2 and back contact of spring d2 to ground. The brushes of the finder of each idle translator are thereby advanced to hunt for the selector OS which has found all junctions in a selected group busy. When the terminals, to which this selector is connected, are found by one of the hunting switches, relay P2 of the finder switch in question is operated by the current in a circuit from ground through contact st1, lower winding of relay P2, brush fm1 and terminal, over conductor T and through contact hs3 of the selector in question to battery. At contact p1, ground is connected through the upper winding of relay P2 to the terminal with

which brush fm1 is in engagement, the potential of this terminal being reduced sufficiently to prevent the operation of the relay P2 of any other hunting finder switch. At the back contact of spring p2, the circuit for operating magnet FM is opened to stop the finder switch and at the front contact of spring p2 a circuit is closed through the lower winding of relay T and resistor BSP. This resistor is common to all of the translators so that the current through the lower winding of relay T will be insufficient to cause the operation of this relay if there is any other translator in the same group then connected to one of the selectors OS and making use of the common marking multiple between the banks of the selectors and the banks of the register switches VR. This marking multiple need not necessarily be a straight multiple. Assuming the multiple to be free, relay T operates and at its contact t1 connects its upper winding in parallel with its operating winding thereby increasing the drop in potential through resistor BSP to prevent the operation of the T relay of any other translator in the group. At contact t3 a circuit is closed through the lower winding of relay B2 to ground at contact d3, but this winding is short-circuited as long as contacts MS are closed. The interrupter contacts MS are opened and closed 10 times per second; and the next opening of these contacts, after relay T operates, causes the operation of relay B2. Relay B2 opens the operating circuit for relay ST at contact b6; but it also closes a locking circuit through the lower winding and contact st3 of relay ST, back contact of spring c1, to ground at contact b2. The actuation of contact spring b2 transfers the interrupter contacts MS through the front contact of spring st4 to the winding of vertical stepping magnet VM2; and the operation of this magnet each time contacts MS are closed raises the brushes of switch VR one step. When the level corresponding to that on which the brushes of switch OS are standing is reached, a circuit is closed from ground at contact t4 through the winding of relay C2, vertical commutator brush vr and segment, through the corresponding segment and the brush VW of the vertical commutator of selector OS in Fig. 1, back contact of spring e1, conductor L, terminal and brush fm2 of the finder F, and through contact t2 to battery. Relay C2 is operated by the current in this circuit. At its back contact spring c1 opens the circuit through the lower winding of relay ST and at its front contact connects this winding through the front contact of spring b2, interrupter contacts MS, contact t3, and the back contact of spring d3 to ground; and the next opening of the interrupter contacts MS causes the release of relay ST. The opening of the front contact of spring st4 prevents the further operation of magnet VM2 and the closing of the back contact of spring st4 connects the winding of relay A2 to the interrupter contacts MS. Relay A is then alternately operated and released under the control of contacts MS. Each operation of relay A closes, at the front contact of spring a3, a circuit for energizing magnet RM2 and, at its contact a1, a circuit from ground on the terminal with which brush fm3 is engaged, through contact g2, brush fm4, over conductor R to the selector OS, front contact of spring hs1, contact e1 and through the winding of rotary magnet RM to battery. Thus the rotary magnet RM2 of the register switch VR of the translator and rotary magnet RM of the selector OS are simul- 75

taneously alternately operated and released, under the control of relay A and interrupter contacts MS, to advance the brushes of each of these switches step-by-step. When the brushes of selector OS reach their eleventh rotary position, the contact springs *s*₁, *s*₂ and *s*₃ are actuated. At the back contact of spring *s*₂, the short circuit around the left winding of relay EL is opened and, the contact *hs*₂ being closed, relay EL operates. The operation of relay EL causes the release of relay C₂, disconnects the + and - conductors incoming from the first selector from the windings of relay A, and closes a circuit from battery through contact *t*₂ of relay T in the translator, brush *fm*₂, conductor L, front contact of spring *el*₁, + conductor to the first selector and register translator, back over the - conductor, through contact *el*₄ and the right winding of relay EL to ground. Relay EL is thus held operated and the register-translator is thus maintained inert. At the front contacts of springs *el*₃ and *el*₅ the windings of relay A are connected over conductors - and +, through brushes *fm*₅ and *fm*₆, and contacts *d*₂ and *b*₄ of relays A₂ and B₂, in series with the upper winding of relay D₂, the contact *a*₂ being closed as soon as springs MS are opened and relay A₂ releases. Relay D₂ is operated by the current through its upper winding, and locks through its lower winding and locks through its lower winding and contact *d*₅ to ground at contact *b*₃. The opening of contact *d*₃ prevents the further operation of relay A₂ and magnets RM₂ and RM, the brushes of switch VR having been advanced to a position complementary to that of the junction group in which all junctions were found to be busy. After relay D₂ operates, relay B₂ is held operated by its upper winding in a circuit through its contact *b*₁, back contact of spring *g*₁ and through the front contact of spring *d*₂. At contact *el*₂, relay EL closes a circuit for operating the release magnet ZM of switch OS; this circuit is traced through contacts *el*₂, *hs*₄, front contact of spring *b*₅ of relay B, and through contacts *n*₅, *ha*₅ and *hb*₅ to ground. When the selector switch reaches normal, the opening of contacts *n*₅ causes the release of relay HS and magnet ZM. Relay A of the selector is held operated over the - and + conductors, through brushes *fm*₅ and *fm*₆, and through contacts *a*₂ and *d*₄ in the translator, the upper winding of relay D₂ being short-circuited by contact *d*₄. The register switch VR having been set to a position indicative of the group in which the selector OS found all junctions busy, the marking multiple between the vertical commutators of the translators and selectors may be released for use by other translators and selectors; to this end the circuit through the winding of relay T is opened at the back contact of spring *d*₂, and relay T releases. With the register switch VR set in a position indicative of the character of the group in which selector OS found all junctions busy, the winding of relay F₂ is connected through contact *d*₆, brush *vrm*₁ and terminal, over the S conductor by which this terminal is connected to relay TA of the translating switch in Fig. 3, through the winding of relay TA, to the normal terminal of the group with which brush *tm*₄ engages. If the translator is then idle, the brush *tm*₄ is in engagement with its normal terminal and relays F₂ and TA are operated. Relay F₂ closes a circuit through the front contact of its spring *f*₃ and the front contact of spring *b*₅ for operating relay G₂. Relay TA closes a circuit at contact *ta*₁ for operating relay TC and as soon as the

interrupter contacts MS of the translating switch are next opened relay TC operates. Contact spring *tc*₁ transfers the interrupter contacts MS to the winding of the translating switch magnet TM and contact *tc*₃ closes a locking circuit for relay TC. If desired, metering relays D₃ may be connected to the S conductors from the bank of switch VR in series with relay TA. The particular D₃ relay, which is included in this circuit for operating relay TA, operates; and the aforementioned operation of relay TC closes a circuit through contact *d*₁ for operating that one of a plurality of overflow meters OM, which is individual to the junction group in which all junctions were found busy. The interrupter contacts IS and MS operate in synchronism, the contacts MS being effective to alternately operate and release the translator stepping magnet TM. The contacts IS are connected to all of the translator switch brushes *tm*₁, *tm*₂, *tm*₃, the banks of which are multiplied to impulse conductors P, leading to the terminals of the bank of switch VR with which brush *vrm*₂ engages. Translated codes are thus obtained for the groups of junctions connected to the bank of switch OS, which codes control the switching operations required for reaching the same offices over alternative routes. For a more complete description of the interconnection of the terminals of the bank of switch VR over conductors P to the terminals of switch TS to give the desired translated codes, reference may be had to the aforementioned Wright Patent No. 1,900,969. The operation of magnet TM under the control of contacts MS advances the brushes of switch TS to transmit the particular alternative route code identified by the setting of switch VR. Relays TA and F₂ are released when brush *tm*₄ leaves the home position. Relay G₂ is held operated through the back contact of spring *f*₃, contacts *g*₅, *d*₅ and the front contact of spring *g*₄. Relay B₂ releases when contact *f*₄ is opened. Each time one of the translator brushes *tm*₁, *tm*₂ or *tm*₃ encounters a terminal to which the conductor P (from the terminal in the bank of switch VR with which the brush *vrm*₂ is in engagement and which identifies the junction group in which all junctions were found busy) is multiplied, the winding of relay A₂ is connected through the front contact of spring *g*₃, contact *f*₁, brush *vrm*₂ and terminal, over a conductor P, terminal and brush *tm*₁, *tm*₂ or *tm*₃, to the interrupter contacts IS. As soon thereafter as these contacts are again closed, relay A₂ is operated, the opening of its contact *a*₂ causing the release of relay A of the selector OS. Switch TS steps on the back stroke of magnet TM so that the stepping does not affect the control of relay A₂ by contacts IS. The impulses corresponding to the first and second digits of the alternative route code are thus transmitted to relay A₂ and through it to relay A of selector OS to operate the vertical magnet VM and rotary magnet RM and thereby again advance the brushes of switch OS to the first set of terminals in the alternative route group in the manner hereinbefore described. When an idle tandem junction in this group is found, relay HA or relay HB operates extending the connection to the selected junction. The remaining code digits are then sent from the special translator by the contacts *a*₂ of relay A of the translator to control the operation of one or more selectors in the tandem or intermediate exchange or exchanges. When all of the code digits, necessary to reach the desired exchange, have been transmitted, re-

lay TB is energized in a circuit through one of the translator brushes and an engaged terminal, which terminal marks the end of a translated code, and through contacts IS to ground. At contact *tb*2 the winding of magnet TM is connected in parallel with the winding of relay TB. The opening of the back contact of spring *tb*1 causes the release of relay TC. After relay TC releases, relay TB is held through contact *tc*2 and through the off-normal terminals with which brush *tm*4 engages until the switch TS is restored to normal. The stepping magnet TM operates through its own interrupting contacts, and through contacts *tb*2 and *tc*2 to the ground on brush *tm*4. When the switch reaches the home position relay TB releases and magnet TM cannot reoperate. While relay TB is operated, ground is connected through the front contact of spring *tb*1 over conductor S to the terminal 20 with which brush *vr*₁ is in engagement, thence through brush *vr*₁ and contact *d*6 to the winding of relay F2 causing the reoperation of relay F2. The operation of relay F2 causes the release of relay G2. The release of relay G2 causes the 25 release of relay D2 and the release of relay D2 causes the release of relay F2. With relays B2, F2 and G2 released the release magnet ZM2 is operated and the register switch VR is restored to normal in usual manner. The release magnet ZM releases when the switch reaches normal and contacts *n*2 are opened.

The aforementioned release of relay D2 opens at its contact *d*1 the above-mentioned circuit through the register-translator and right winding of relay EL of the selector OS. The release of relay EL completes at the back contacts of springs *el*3 and *el*5 the connection from the first selector and register translator, through the brushes of selector OS to the seized junction and 40 through the tandem office to the desired office. The register-translator thereupon controls the completion of the desired connection in usual manner.

It may be desirable to connect more than one group of selectors OS, to the finder switches of a group of translators in which case it is then desirable that there be no interference between the two groups in controlling the setting of the register switch VR. To this end the relay E2 45 may be provided in which case ground is directly connected to the terminals engaged by brush *fm*3 and which are associated with the selectors of one group; but the terminals with which brush *fm*3 engages and associated with the other selector group are not connected directly to ground. When a selector of the second group calls in an 50 alternative route translator the first operation of relay A2, while effective to operate magnet RM2 and advance switch VR one step, is ineffective to operate magnet RM of the selector because the terminal with which brush *fm*3 is in engagement is not connected to ground. When relay A2 releases after switch VR takes the first rotary 55 step, the closing of the rotary off-normal springs *nr*1 causes the operation of relay E2; the circuit for relay E2 is traced through the back contact of spring *e*2, contact *nr*1, and back contacts of springs *a*3 and *g*4. Relay E2 locks through 60 contacts *e*2 and *b*3. At contact *e*1, ground is connected to contact *a*1 so that each succeeding 65 operation of relay A2 causes the operation of magnet RM of the selector as well as the operation of magnet RM2 of switch VR. The 70 switch VR is thus given one more step when the 75

associated selector is in one group than when it is in the other for the same position of the selectors and the possibility of interference between the two groups is thereby minimized.

On certain routes, such as a group of long distance lines of a character which provides high grade transmission, it is undesirable to provide alternative trunking. In such a case, the selector is redirected under the control of the special translator to a level in which the brushes will 10 be automatically advanced eleven steps to the eleventh rotary position in which position contact springs S1, S2 and S3 are again actuated. The special translator is released and the selector reconnected to the register-translator to indicate the busy condition, whereupon release 15 again takes place as hereinbefore described.

Consider now the embodiment of the invention illustrated in Figs. 4 and 5. In this system two digits determine the exchange in which a wanted subscriber is located. A calling subscriber's line is connected to a first selector which in response to the first digit dialed selects an idle second selector. The second selector is a one-digit selector and, in response to the second digit 20 dialed, selected a group of junctions outgoing to the wanted exchange and selects an idle junction in this group. One of these second selectors OS4 is represented in Fig. 4, only the apparatus required for a disclosure of the invention being 25 shown. With each group of 25 second selectors, there is associated a group of three link circuits one of which is shown in Fig. 4. Each link comprises a selector finder switch SF having access to 30 25 second selectors and a register finder RF 35 having access to a group of 5 or 6 register-translators RC, the translators being common to all of the links in the exchange. When a second selector finds all junctions busy in a selected 40 group it calls into service a link and a translator which thereupon assumes control of the rerouting of the call and which also receives and registers the numerical digits dialed by the calling subscriber. The second selector is released from 45 its set position and is selectively reoperated to seize an idle junction to a tandem exchange. This translator then controls switching operations in the tandem exchange to select an idle junction leading to the called exchange and the 50 numerical selections in the called exchange.

When a second selector is seized and, in response to the second digit dialed by the calling subscriber, is moved out of normal, the off-normal contact *n*2 closes and relay X operates in series with the release magnet ZM4. The release magnet is marginal and does not operate in series with relay X. At contact *x*1 a circuit is closed for operating the common start relay SA. At contact *sa*, relay SA closes circuits for 55 operating relay ST4 of each free link in the group associated with the group of second selectors to which relay SA is common. In each such link relay ST4 closes, at contact *st*2, a circuit for operating the selector-finder magnet SFM. When the brushes of a finder engage the terminals to which the selector OS4 is connected, a circuit is closed through brush *sfm*1 and both windings of relay P4 to ground at contact *st*1. Relay P4 operates and at its contact *p*2 short-circuits its 60 right winding, thereby decreasing the potential of the terminal with which brush *sfm*1 is engaged to cause the release of relay SA and thereby stop the hunting of the other links. In the 65 successful link, the operation of relay P4 opens 70 75

- the operating circuit of magnet SFM and at the front contact of spring p_1 closes a circuit for operating relay PP. At contact pp_5 , relay PP opens the operating circuit of relay ST4. At 5 the front contact of spring pp_4 , relay PP closes a circuit for operating the finder magnet RFM; this circuit includes the back contact of spring t_2 , brush rfm_1 of the register-finder switch and the back contact on_1 of any register-translator 10 with the terminals of which the brushes of switch RF are then in engagement. If this translator is busy, the ON relay is not operated and the magnet RFM is energized to step the brushes to the next set of terminals. When the brushes 15 encounter a set of terminals to which an idle translator is connected, the ON relay of this translator being operated, contact on_1 is open and magnet RFM cannot reoperate; and the hunting operation is ended.
- 20 If the second selector OS4 finds an idle junction in the selected group, the operation of the usual switching relay H, the winding of which is not shown in the drawings, opens at contact h_1 the operating circuit of relay X. The release 25 of relay X causes the release of relay P4 of the associated link and the translator is not brought into action.
- If, however, the selector finds all of the junctions in the selected group busy and the level of 30 this group is one arranged for alternative routing, the eleventh step springs are actuated when the brushes reach the eleventh rotary position. The operating circuit for relay X is opened at contacts s_2 , and a circuit is closed from ground 35 at contact b_1 , through the off-normal springs n_1 , eleventh rotary step spring s_1 , winding of relay K, and through brush sfm_3 and contact pp_1 of relay PP of the associated link. Relay K operates in this circuit; locks through its contact k_2 ; 40 and closes, at its contact k_1 , a circuit through brush sfm_2 , contact pp_1 of relay PP of the link, winding of relay T4, front contact of spring pp_4 and winding of magnet RFM. Being marginal magnet RFM does not reoperate, but relay T4 45 operates. Relay T4 closes a holding circuit for relay PP through contacts pp_6 and t_1 , and through brush rfm_6 to ground at the back contact r_1 of relay R of the associated translator. Relay P4 of the link releases when relay X of the 50 selector is released. Since relays P4 and PP of the link are slow in releasing, the above traced holding circuit for relay PP is closed soon enough to prevent the release of this relay. The aforementioned operation of relay K opens at contacts k_3 and k_4 the normal connection between the incoming - and + conductors and relay A4 55 of the selector OS4; but relay A4 remains connected to the calling loop through brushes sfm_6 and sfm_7 , contacts pp_2 and pp_3 , back contacts of springs t_3 and t_4 and brushes sfm_4 and sfm_5 60 until relay T4 operates. Relay T4 interconnects the selector and register-translator, the calling subscriber's loop being disconnected from the windings of relay A4 and connected through the 65 front contacts of springs t_3 and t_4 and brushes rfm_2 and rfm_3 to the windings of relay RA in the register-translator. Relay A4 is held operated through contacts t_5 and t_6 , brushes rfm_4 and rfm_5 , back contact of spring r_2 of relay R 70 in the register-translator, contact sa_2 and through contacts mf_2 and mg_5 in parallel. Relay RA operates over the calling subscriber's loop, closing at the front contact of spring ra_1 a circuit for operating relay RB; and relay RB 75 closes at contact rb_2 a circuit for operating relay

BB. The opening of contact rb_3 causes the release of relay ON. The closing of contact on_1 connects ground to the terminal with which brush rfm_1 is in engagement, through the front contact of spring t_2 in the link, to the winding 5 of relay T4 to hold relay T4 operated independent of the ground potential on the sleeve conductor P of selector OS4. Relay BB of the translator completes a circuit for operating relay MG from the common resistor BS in the link, 10 through contact t_9 and brush rfm_1 , contact bb_9 of relay BB, contact mf_3 and through both windings 15 of relay MG in series. Relay MG operates if the MG relay of none of the other translators is operated when relay BB of the translator in question operates. At contact mg_1 , the high resistance right winding is short-circuited to increase the drop in potential through resistor BS and thereby prevent the operation of the MG relay of any other translator while the common 20 marking multiple between the vertical commutators of the selectors and the banks of register switches BS of the translators is in use by the translator whose operation is being described. Relay MG closes the operating circuit of the self- 25 interrupting stepping magnet BSM of switch BS through contact mg_3 , back contact of springs m_1 and m_6 to ground at the front contact of spring bb_1 . Each of the groups of terminals with which brush bsm_1 of switch BS engages, is connected 30 by a common marking multiple to the commutators of the selectors in a different group of second selectors; and when brush bsm_1 engages the terminal which is connected to the commutator segment with which brushes vm of the second 35 selector in question are in engagement, relay M of the translator operates, the opening of the back contact of spring m_1 preventing the further advance of switch BS; the circuit for operating relay M is traced through contact mg_2 , 40 brush bsm_1 , common marking multiple conductor, commutator wipers vm of selector OS4, brush sfm_8 of switch SF, contact t_8 of link relay T4, brush rfm_8 of switch RF, to ground at contact mg_6 of relay MG of the translator. At the 45 front contact of spring m_1 , relay M closes a circuit for operating relay MF; and relay MF locks through the front contact of its spring mf_6 , to ground at contact bb_1 . Both of contacts mf_2 and mg_5 having been opened, relay A4 of selector 50 OS4 releases, causing the release of relay B (winding not shown). The release magnet ZM4 is thereupon operated through contacts n_2 , b_2 , a_1 and h_1 , the brushes of selector OS4 being thereby restored to normal. Relay M of the 55 translator releases when the selector is restored. Relay MF having been operated and relay M released, both of contacts mf_3 and m_2 are open and relay MG releases. The common marking multiple between the second selectors and switches BS of the translators is thereby released. 60

The release of relay MG closes, at contact mg_5 , the above described circuit through brushes rfm_4 and rfm_5 for operating relay A4 of selector OS4. 65 The release of relay MG also closes a circuit through the winding of relay CC and contact r_3 , mg_4 , s_2 and mf_4 ; and, as soon after this circuit is closed as the interrupter contacts MS are opened, relay CC operates. At the front contact 70 of spring cc_1 , the winding of stepping magnet SSM of switch SS is connected to the interrupter contacts MS, which contacts are opened and closed ten times per second. Each operation of magnet SSM advances the brushes ssm_1 , ssm_2 75

and *ssm3*. When brush *ssm3* engages terminal 4, a circuit is closed through this brush and contacts *m5* and *s23* for operating relay *SA*. Relay *SA* is held in this circuit until relay *SZ* operates during the next 11 additional steps of switch *SS*. At contact *s2*, relay *SA* opens the short circuit around impulse springs *IS*, which springs are also opened and closed ten times per second. Each opening of springs *IS*, after contact *s2* is opened, causes the release of relay *A4* of selector *OS4*, the brushes of this selector being raised one step by each operation of relay *A4* in usual and well-known manner. Assume that the tandem office junctions, which constitute the route alternative to the group in which the selector *OS4* found all junctions busy, are located in the sixth level of the bank, so that the brushes are to be raised to the sixth level by the operation of relay *A4* under the control of springs *IS*. In this case the terminal, with which brush *scm3* of switch *SC* is in engagement when in normal position, is connected to the terminal with which brush *ssm2* of switch *SS* is in engagement in the tenth off-normal position. Six impulses having at that time been sent to relay *A4*, a circuit is closed from ground at the front contact of spring *m1*, through brush *scm3* and normal terminal, terminal 10 and brush *ssm2*, contact *s4*, and lower winding of relay *SZ*. Relay *SZ* locks through contact *s24* and brush *ssm1*; and contact *s2* of relay *SZ* shorts-circuits the impulse springs *IS* to prevent the transmission of another impulse to relay *A4*. The selector *OS4* thereupon hunts in the sixth level for an idle junction to the tandem office and upon finding one, the operation of the cut-through relay (not shown) connects the seized terminals to the register-translator impulse loop in place of relay *A4*. At contact *s26*, the operating circuit of relay *CC* is opened and relay *CC* releases; at contact *s23*, the operating circuit of relay *SA* is opened and relay *SA* releases; at contact *s25*, the magnet *SSM* is connected to brush *ssm1* and the brushes of switch *SS* are thus advanced to normal; and at contact *s27* a circuit for operating stepping magnet *SCM* of switch *SC* is closed. When switch *SS* reaches normal, relay *SZ* releases and opens the operating circuit of magnet *SCM*; the release of magnet *SCM* advances the brushes *scm1*, *scm2* and *scm3* to the first off-normal position. Relay *CC* reoperates when relay *SZ* releases and the contacts *MS* are next opened; and the stepping magnet *SSM* is energized each time contacts *MS* are closed to again advance the brushes of switch *SS*. Relay *SA* reoperates when position 4 is reached and is held until relay *SZ* operates during the next 11 additional steps. The selections to be controlled in the tandem office determine the digits transmitted by contacts *IS* to the tandem office, an impulse being transmitted by each closure of these contacts after contact *s2* is opened by the reoperation of relay *SA*. The first off-normal terminal, with which terminal brush *scm3* is in engagement is connected to brush *bsm2* and through cross connecting conductors *CCF* to the desired one of terminals 4 to 13, inclusive, with which brush *ssm2* engages; and, when brush *ssm2* encounters the particular terminal which is connected to the terminal with which brush *bsm2* is in engagement, relay *SZ* is reoperated to end the first train of digit impulses being transmitted to the tandem office. Relay *SZ* causes switch *SC* to be advanced to the second off-normal position and a second

digit is sent to the tandem office in the same manner, the circuit for operating relay *SZ* a third time to end the second digit transmitted to the tandem office being traced through brush *scm3* and second off-normal terminal, brush *bsm3* and terminal with which it is in engagement, over one of cross connecting conductors *CCF* to the terminal with which brush *ssm2* is then in engagement and through contact *s4* to the lower winding of relay *SZ*. When all selections necessary to reach the wanted exchange have been transmitted from the translator, the further progress of the call depends upon the numerical digits dialed by the calling subscriber; and during the transmission of the office code digits and wholly independent thereof, these numerical digits have been received by relay *RA* and registered by switches *MS*, *HS*, *TS* and *US*. Each release of relay *RA* in response to the impulses of the thousands digit closes a circuit from ground through the back contact of spring *ra1*, contacts *rb1* and *r4*, winding of relay *C5*, brush *dd3* in normal position, to stepping magnet *MSM* of the thousands register switch. Relay *C5* operates in series with the stepping magnet and being slow in releasing remains operated until all of the impulses in the train created by the dialing of the thousands digit have been received by relay *RA*. Relay *C5* closes a circuit at contact *c1* for operating stepping magnet *DDM* of switch *DD*. When relay *C5* releases at the end of the digit, magnet *DDM* releases thereby advancing the brushes *dd1*, *dd2* and *dd3* to the first off-normal set of terminals. In response to the hundreds digit, relay *RA* is effective to operate the stepping magnet *HSM* of the hundreds register through brush *dd3* and terminal 1; in response to the tens digit, relay *RA* is effective to operate the stepping magnet *TSM* of the tens register through brush *dd3* and terminal 2; and in response to the units digit, relay *RA* is effective to operate the stepping magnet *USM* of the units register through brush *dd3* and terminal 3. At the end of the units digit, the release of relay *C5* again causes the release of magnet *DDM* and the brushes of switch *DD* are advanced to the fourth off-normal position and no additional impulses will be registered. The numerical digits may be sent out as soon as they are registered and the preceding digit has been sent. In order that the thousands digit will not be sent until completely received, relay *SZ* is held operated, after the second digit has been transmitted to the tandem office, until switch *DD* has advanced out of normal position; the circuit for holding relay *SZ* is traced through its upper winding and contact *s4*, brush *scm2* in second off-normal position, brush *ddm2* in normal position to ground at the front contact of spring *bb5*. In like manner relay *SZ* is held through brush *scm2* in off-normal positions 3, 4 and 5 and brush *dd2* in off-normal positions 1, 2 and 3 so that each of the hundreds, tens and units digits must have been completely received before it can be transmitted to the called exchange. The sending switch *SS* is reoperated, as hereinbefore described to send each one of the numerical digits, the circuit for operating relay *SZ* to end the thousands digit being traced through contact *s4*, brush *ssm2*, the cross-connecting multiple *sz*, terminal with which brush *msm2* is in engagement, and brush *scm3* in third off-normal position; to end the sending of the hundreds digit, the circuit for operating relay *SZ* includes

brush *scm3* in fourth off-normal position and the terminal with which brush *hsm2* is in engagement; to end the sending of the tens digit, the circuit for operating relay *SZ* includes brush *scm3* in fifth off-normal position and the terminal with which brush *tsm2* is in engagement; and to end the sending of the units digit, the circuit for operating relay *SZ* includes brush *scm3* in sixth off-normal position and the terminal with which brush *usm2* is in engagement.

When the units digit has been received and transmitted, the operation of relay *SZ* closes at contact *sz1* the circuit for operating magnet *SCM* whereby switch *SC* is stepped to the seventh off-normal position, in which position relay *R* is operated by the energization of its lower winding, through brush *scm3* in the seventh off-normal position to ground at the front contact of spring *mfl*. The operation of relay *R* causes the release of relay *PP* of the link; and the release of relay *PP* causes the release of relay *K* of the selector *OS4* and the release of relay *T4* of the link. Relay *K* releases quickly and relay *T4* releases slowly. When relay *K* releases, the calling subscriber's loop is connected through contacts *k3* and *k4* to the brushes (not shown) of the selector *OS4* thus completing the connection between the calling and called lines. When relay *T4* releases, the opening of contacts *t3* and *t4* disconnects the calling line from relay *RA*. After relay *PP* releases and before relay *T* releases, the resistor which is normally short-circuited by contact *r2* of relay *R* is connected in the loop across contacts *t5* and *t6* so that the release of relay *K* will not cause excessive noise at the calling station. The release of relay *RA* causes the release of relays *RB*, *BB* and *MF* in succession. Switches *MS*, *HIS*, *TS*, *US*, *SS*, *SC* and *DD* are thereupon advanced to normal by operation of their stepping magnets through brushes *msm1*, *hsm1*, *tsm1*, *usm1*, *ssm1*, *scm1* and *dd1* respectively. Switch *BS* is a non-restoring switch. When all of the numerical register switches are normal, relay *ON* reoperates and opens at contact *on2* a holding circuit for relay *R*. Contact *on1* disconnects ground from the terminal with which brush *rfl1* of finder *RF* is in engagement, thereby causing this register-translator to test idle.

If a selector *OS4* is advanced into the eleventh rotary position on a level for which there is no alternative route, the link is seized while the selector is being stepped up to this level and the register-translator is seized when the eleventh rotary stop springs are actuated as hereinbefore described. Relay *MG* operates and switch *BS* hunts for the level to which the brushes of switch *OS4* have been set. The vertical commutator segments of all levels for which alternative routes are not provided are connected to one terminal 60 of the bank with which brush *bsm1* engages. When brush *bsm1* encounters this terminal, relays *M* and *MF* are operated as hereinbefore described. No alternative route translation being required, relay *R* is immediately operated, when relay *MF* operates, in a circuit through brush *bsm4* in normal position to ground at contact *mfl*. The operation of relay *CC* is thus prevented by the opening of contact *r3* so that no digits can be transmitted. Relays *PP* and *T4* of the link and relay *K* of the selector are released as hereinbefore described. Upon release of relay *K*, a busy tone circuit (not shown) is closed to transmit a busy tone to the calling station. Contact *s2* prevents the operation of relay *X* after relay *K* releases.

A forced release of the register-translator may occur at any stage of its use in case an interval of from 18 to 27 seconds has elapsed after the operation of relay *BB*. At contact *bb8*, the upper winding of relay *ZA* is connected to an impulse conductor to which ground impulses of .75 second duration are connected at intervals of 9 seconds. The first ground impulse after relay *BB* operates causes the operation relay *ZA* sufficiently to actuate only its contact *za1*, at the end of the impulse relay *ZA* is completely operated by its windings in series. The next impulse, 9 seconds later, energizes the upper winding of relay *ZB* sufficiently to actuate only its contact *zb1*; and at the end of the impulse relay *ZB* is completely operated by its windings in series. At the front contact of spring *zb2*, the upper winding of relay *R* is then connected to the 9 second impulse conductor; and, after 9 seconds more, the next impulse causes the operation of relay *R*. The release of the register-translator is thereby forced by the operation of relay *R* irrespective of the stage of the call. In such a case, if the selector *OS4* has seized an idle outgoing junction, the calling subscriber could obtain completion of the call by dialing whatever digits remained to be dialed.

If the calling subscriber releases the connection at any time after the line is connected to relay *RA* of the register-translator, relays *RA*, *RB* and *BB* release. Relay *R* is then operated through contact *on2* and *bb7* to cause the release of the link and the return of all switches to normal as hereinbefore described.

What is claimed is:

1. In a telephone system, a selector switch for use in establishing desired connections, groups of lines connected to the bank of said switch, means for advancing the brushes of said switch to select any desired one of said groups of lines, means for hunting for an idle line in a selected group, a register switch, and means effective if no idle line is found in a selected group for operatively associating said register switch with said selector switch.

2. In a telephone system, a selector switch for use in establishing desired connections, groups of lines connected to the bank of said switch, means for advancing the brushes of said switch to select any desired one of said groups, means for hunting for an idle line in a selected group, a register-translator comprising a register switch and a translator switch, and means effective if no idle line is found in a selected group for operatively associating said register-translator with said selector switch.

3. In a telephone system, according to claim 1, means for advancing said register switch and selector switch simultaneously one step at a time.

4. In a telephone system, according to claim 1, means comprising vertical commutators of said selector and register switches for identifying the group in which no idle line was found.

5. In a telephone system, a two-motion selector switch for use in establishing desired connections, groups of lines connected to the bank of said switch, means for advancing the brushes of said switch to select any desired one of said groups of lines, means for hunting for an idle line in a selected group, a register switch, means effective if no idle line is found in a selected group for operatively associating said register switch with said selector switch, means comprising vertical commutators of said selector and register switches for identifying the terminal level in which said selected group is located, and means

for advancing said register switch and selector switch simultaneously one step at a time to complete the identification of said group.

6. In a telephone system according to claim 1, means for advancing said register switch to identify the group in which no idle line was found, and means comprising a translator switch for determining the identity of another one of said groups which other group constitutes an alternative route to the group in which no idle line was found.

7. In a telephone system according to claim 1, means for advancing said register switch to identify the group in which no idle line was found, and means effective upon completion of the identification of said group for returning said selector to normal.

8. In a telephone system according to claim 1, means for advancing said register switch to identify the group in which no idle line was found, means effective upon completion of the identification of said group for returning said selector to normal, and means comprising a translator switch for controlling the reoperation of said selector to select another one of said groups which other group constitutes an alternative route to the group in which no idle line was found.

9. In a telephone system, a selector switch having groups of lines connected to its terminal bank, each group leading to a different exchange, means for advancing the brushes of said switch to select the one of said groups which leads to a called one of said exchanges and for advancing the brushes to hunt for an idle line in the selected group, a register switch, means effective if no idle line is found in the selected group for operatively associating said register switch and selector switch, means for advancing said register switch to identify the group in which no idle line was found, and translator means for determining the code for controlling the completion of the desired connection over an alternative one of said groups and through another one of said exchanges to said called exchange.

10. In a telephone system, a selector switch having groups of lines connected to its terminal bank, each group leading to a different exchange, means for advancing the brushes of said switch to select any desired one of said groups and for advancing the brushes to hunt for an idle line in a selected group, a register-translator comprising a register switch and a translator switch, means effective if no idle line is found in a selected group for operatively associating said selector switch with said register-translator, means for advancing said register switch to identify the group in which no idle line was found, and means comprising said translator switch for determining the code of an alternative route over which the desired connection can be established.

11. In a telephone system, a selector switch having groups of lines connected to its terminal bank, each group leading to a different exchange, means for advancing the brushes of said switch to select any desired one of said groups and for advancing the brushes to hunt for an idle line in a selected group, a register switch, means effective if no idle line is found in a selected group for operatively associating said selector switch and register switch, means for advancing said register switch to identify the group in which no idle line was found, means effective upon completion of the identification for returning said selector switch to normal position, and translat-

ing means for controlling the reoperation of said selector switch to select an alternative group of trunks over which the desired connection can be completed.

12. In a telephone system, a selector switch having groups of lines connected to its terminal bank, each group leading to a different exchange, means for advancing the brushes of said switch to select any desired one of said groups and for advancing the brushes to hunt for an idle line in a selected group, a register switch, means effective if no idle line is found in a selected group for operatively associating said register switch and selector switch, means for advancing said register switch to identify the group in which no idle line was found, means effective upon completion of the identification for returning said selector switch to normal position, and translating means for determining the code of an alternative route.

13. In a telephone system, a selector switch having groups of lines connected to its terminal bank, each group leading to a different exchange, means for advancing the brushes of said switch to select any desired one of said groups and for advancing the brushes to hunt for an idle line in a selected group, a register switch, means effective if no idle line is found in a selected group for operatively associating said register switch and selector switch, means for advancing said register switch to identify the group in which no idle line was found, means effective upon completion of the identification for returning said selector switch to normal position, and translating means for determining the code of an alternative route, for transmitting the first digit of said code to control the reoperation of said selector switch and selection of a group leading to a tandem office, and for transmitting the remaining digits of said code to control the extension of the connection through the tandem office to the wanted office.

14. In a telephone system, groups of selector switches for use in completing desired connections, groups of lines multipled to the terminal banks of a group of said selectors, each of said groups leading to a different exchange, means in each of the selectors for advancing its brushes to select any desired one of said groups of lines and for advancing its brushes to hunt for an idle line in a selected group, translators, links for connecting the translators to the selectors, means effective upon one of said selectors finding no idle line in a selected group for starting the operation of a link to operatively associate one of said translators with said selector, register means in said associated translator for determining the group in which no idle line was found, means effective upon completion of the identification of said group for causing the return of said selector to normal, and means in said translator for sending the code digits of an alternative route for controlling the reoperation of said selector to select a group of lines to a tandem exchange and for controlling the extension of the connection through said tandem exchange to the called exchange.

15. In a telephone system, a two-digit selector switch having groups of lines connected to its terminal bank, each group leading to a different exchange, means for receiving digit impulses for controlling the operation of the switch, means responsive to a first one of two digits for advancing the brushes of the switch to a corresponding level of the terminal bank, means responsive to the second one of said digits for advancing the

brushes to select a desired group in a selected level, means for advancing the brushes to hunt for an idle set of terminals in said desired group, translators, means effective if the brushes of said selector switch are advanced to the last set of terminals in the desired group without finding an idle line for operatively associating an idle one of said translators with said selector, a register switch in said translator, means for advancing the brushes of said register switch to a level corresponding to said selected level of said selector switch, means for advancing the brushes of said register switch one step at a time and for simultaneously advancing the brushes of said selector switch one step at a time until the brushes of said selector switch reach the eleventh rotary position, the terminal with which the brushes of said register switch are then in engagement being indicative of the digit code by which said desired group of lines is selected.

16. In a telephone system, a group of two-digit, selector switches for use in establishing desired connections, another group of such switches, groups of lines connected to the banks of the switches in one group of selectors, other groups of lines connected to the banks of the switches in the other group of selectors, each group of lines leading to a different exchange, means in each selector for advancing its brushes to select a desired level, a desired group of terminals in said level and an idle line in said group, translators, means effective upon the brushes of one of said selectors being advanced to the last set of terminals in a desired group without finding an idle line for operatively associating said selector with an idle one of said translators, a register switch in said translator, means for advancing

the brushes of said register switch to a level corresponding to the level selected by the brushes of said selector switch, means for simultaneously advancing the brushes of said register switch and the brushes of said selector switch step-by-step until the brushes of said selector reach the eleventh rotary position in the level, and means effective only if said selector is in one of said groups for advancing the brushes of said register one step without at the same time advancing the brushes of said selector switch before said simultaneous stepping of said switches begins.

17. In a telephone system, groups of selector switches used in completing desired connections, different groups of lines multiplied to the banks of each group of selectors, each group of lines leading to a different exchange, means in each selector for advancing its brushes to select a desired level and an idle line in the desired group, a translator, link means effective upon all of the lines in a desired group being found busy by one of said selectors for operatively associating said translator and selector, group identifying terminals for said selectors, a register switch in said translator, groups of terminals in the bank of said register switch, the terminals in each group being multiplied to the group identifying terminals of the selectors in a different one of said groups of selectors, and means including said group identifying terminals for advancing the brushes of the register switch to the terminal corresponding to groups in which the selector found all lines busy.
